UNITED STATES PATENT OFFICE.

WILLIAM L. DAVIS, OF DAYTON, OHIO.

DESIGN FOR A RADIATOR CAP.

Application filed April 10, 1922. Serial No. 1,682. Term of patent 3½ years.

To all whom it may concern:

Be it known that I, WILLIAM L. DAVIS, a citizen of the United States, residing at Dayton, county of Montgomery, and State of Ohio, have invented a new, original, and ornamental Design for Radiator Caps, of which the following is a specification, reference being had to the accompanying drawing, forming part thereof.

Fig. 1 is a side elevation of a radiator cap embodying my new design; Fig. 2 is a top plan view; and Fig. 3 is an end elevation of the same.

I claim:

The ornamental design for a radiator cap, as shown.

WILLIAM L. DAVIS.
